(57) **CLAIM**

We claim, the ornamental design for an outdoor storage shed, as shown and described.

DESCRIPTION

FIG. 1 is an isometric view of an outdoor storage shed;

FIG. 2 is a front view thereof;

FIG. 3 is a rear view thereof;

FIG. 4 is a left side view thereof;

FIG. 5 is a top view thereof; and,

FIG. 6 is a bottom view thereof.

The right-side view is omitted because it is a mirror image of their respective left side view. The parts colored in white and delineated with dashed lines illustrate portions which are not part of the claimed design.
